(57) **CLAIM**

The ornamental design for a mouthguard, as shown and described.

DESCRIPTION

FIG. 1 is a front perspective view of a mouthguard illustrating my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a bottom view thereof;

FIG. 8 is a top view thereof; and,

FIG. 9 is another front perspective view of the mouthguard coupled to an optional lip guard.

In FIGS. 1-9, the uniformly-sized broken lines immediately adjacent to the shaded areas depict the bounds of the claimed design, while all other uniformly-sized broken lines are directed to environment. In FIG. 9, the long-short broken lines illustrate an optional environment of a lip guard that forms no part of the claimed design. None of the broken lines form part of the claimed design.
